UNITED STATES PATENT OFFICE.

RALPH L. SKINNER, OF DETROIT, MICHIGAN, ASSIGNOR TO SKINNER AUTOMOTIVE DEVICE CO., INC., OF SACRAMENTO, CALIFORNIA, A CORPORATION OF CALIFORNIA.

SLEEVE TYPE OF INTERNAL-COMBUSTION ENGINE.

Application filed December 8, 1922. Serial No. 605,565.

To all whom it may concern:

Be it known that I, RALPH L. SKINNER, a citizen of the United States, residing at Detroit, in the county of Wayne and State of Michigan, have invented certain new and useful Improvements in Sleeve Type of Internal-Combustion Engines, of which the following is a specification.

My invention relates to improved and novel means for withdrawing fluids from around the reciprocatory pistons of internal-combustion motors or engines, whereby to prevent the passage of the lubricating oil upwardly by the pistons into the combustion or explosion chambers, where its presence is likely to form carbon deposits and to foul or short-circuit the spark-plugs, and to prevent the downward passage of liquids and gases including unconsumed fuel and the products of combustion, past the pistons into the crank-case of the engine where they dilute and contaminate the oil supply.

This broad idea forms the subject-matter of a companion co-pending patent application, Serial Number 472,746 filed May 26th, 1921, the current invention relating more particularly to engines having one or more sliding sleeves around the pistons and concerning more especially engines of the Knight type wherein each cylinder is fitted with two reciprocatory sleeves one within another, although the invention in its broader aspects relates to constructions using poppet or other valves, and to those wherein a single reciprocating sleeve is used to control the cylinder port at which suction is applied to withdraw the fluids referred to.

In the Knight style of engine it is also desirable to draw off fluids, principally lubricating oil, from the annular chamber at the tops of the nested sleeves to prevent their passage by the rings in the head of the cylinder into the combustion chamber.

To enable those skilled in this art to have a full and complete understanding of the invention and its various advantages, in the accompanying drawings forming a part of this specification and throughout the several views of which like reference characters have been employed for the same parts, there have been shown two desirable embodiments of the invention.

In these drawings:

Figure 1 is a sectional view of one cylinder of a Knight type of engine fitted with the improvement constituting the subject-matter of this invention including an oil separating tank or trap;

Figure 2 is a face view of the piston used in such engine;

Figure 3 is a fragmentary section through a side of the piston wall; and

Figure 4 shows in section an engine of the poppet valve type equipped with a single reciprocatory sleeve between the piston and cylinder, the appliance also having the lubricating oil separating tank or trap.

Referring first to the appliance depicted in Figures 1, 2 and 3 of the drawings, it will be seen that the motor illustrated includes the usual water-jacketed cylinder 11 having a detachable, water-cooled head 12 equipped with a spark-plug 13, an outer sleeve 14 reciprocated by an eccentric mechanism 15 and having two ports 16 and 17 through it adapted to cooperate with the exhaust and inlet ports 18 and 19 respectively through the upper portions of the cylinder-wall, and an inner sleeve 21 actuated by an eccentric appliance 20 and having ports 22 and 23 designed to co-act in the usual manner in the Knight type of engine with the ports of the outer sleeve and the ports of the cylinder.

As is customary in this style of engine the cylindrical portion of the cylinder-head projecting into the cylinder inside of the inner sleeve is fitted with the usual rings 24, 25, and 26 bearing outwardly against the internal face of the inner sleeve to maintain a compression-proof relation therewith, hence preventing escape of fluids under pressure in the cylinder into the chamber 27 between the cylinder and the cylinder-head above the companion sleeves.

Inside of the inner sleeve, the reciprocating piston 28 is employed being associated with the crank-shaft, not shown, by the connecting-rod 29, and the cylinder, piston, and sleeves are lubricated in the usual way by the splash or forced feed system or a combination of the two or in any other suitable manner.

Around its upper portion only, this piston has a plurality of piston-ring grooves and

their piston-rings 31, 32, and 33 the lower-most ring 33 being annularly channeled at 34 on its inner face, its piston groove 35 being somewhat deeper than the others, the outer face of the piston below such lower ring having a longitudinal groove 36 communicating at its upper end by a channel 37 with the lower piston-ring groove back of its ring.

10 In the two embodiments of the invention, as shown in Figures 1 and 4, the pistons are alike, and it is to be noted that diametrically opposite the lengthwise, external channel 37, such lower piston-ring groove has an air 15 inlet passage or port 40 extended inwardly through the piston-skirt into the hollow interior of the piston and hence communicating with the air in the crank-case.

At the point 38, the cylinder side wall is 20 supplied with a port or opening fitted with a pipe 41 extended through the water-jacket to the outside of the cylinder, and, in similar manner, the chamber 27 has a port 42 leading to the outside of the cylinder 25 wall, these two ports or openings 38 and 42 being in line with the path of travel of the piston groove 36.

This upper chamber or compartment 27 is also supplied, opposite port 42, with an air 30 inlet port 43 extended to the outer air through a small wall 44 traversing the water-jacket of the cylinder-head.

The two pipes 45 and 46 for the two ports 38 and 42 are connected to a single pipe 47 35 delivering into an oil separator or trap 48 of any suitable design, the upper portion of the interior of such tank and hence the two ports 38 and 42 connected thereto being subject to the sub-atmospheric pressure or 40 suction of the intake manifold of the engine by reason of the pipe 49 which connects the tank to such manifold, the lower end of the tank having a delivery pipe 51 by means of which the separated or reclaimed oil is 45 returned to the crank-case, the tank or separator being heated, if desired, although this is not always necessary, to facilitate the separation.

50 The construction of a tank suitable for this purpose is presented in detail in my co-pending patent application, Serial Number 587,026, filed September 8th, 1922.

The inner sleeve 21 has a port or opening 52 therethrough in line with the cylinder port 38 and during the movements of the sleeve it is adapted to be brought into register therewith.

On the other hand, the outer sleeve 14 60 has two spaced ports 53 and 54 in line with the ports 52 and 38 and designed at the right moments to be brought opposite such ports and to establish communication between the two.

When the ports of both sleeves are opposite the cylinder port, then the suction ex-

erted in the separating tank and piping system is operative through the channels 36 and 37 to withdraw the accumulated fluids in the lower-most piston-ring groove, but when the sleeve ports are out of register, the suction action around the piston is temporarily interrupted.

Of course, the groove or channel 36 on the outer face of the piston is in operative relation with the port of the inner shell or sleeve 75 during a large portion of the piston stroke and by using a plurality of ports in the outer sleeve co-acting with the port of the inner sleeve, the suction exerted on the cylinder port is rendered active on the piston 80 and its piston-ring groove during a material part of the reciprocatory movement of the piston, whereby an effective withdrawal of the fluids is assured, the separation occurring in the trap, the gases, vapor, and air 85 passing to the intake manifold under the suction action, the reclaimed oil being returned to the crank-case intermittently under atmospheric pressure.

When the cylinder port would be otherwise uncovered by the piston skirt, it is closed by the one or the other sleeve so that the suction condition of the system is not interfered with by an inrush of air through such port.

At the same time, the constantly applied suction to the chamber 27 withdraws the oil which accumulates therein passing upwardly into such compartment between the sleeves and between the outer sleeve and the cylinder, this removal of the oil being assisted by the air entering the vent 43 which not only facilitates the suction withdrawal of the oil but also aerates the oil preparing it for treatment in the separator.

This is also true of the piston-ring groove air vent or bleeder port 40 which permits the entrance of air to the groove hence aiding in the discharge of its contents and mixing the oil with the added air in which condition it is abstracted from around the piston.

Thus the oil is prevented from passing down by the piston-rings of the stationary cylinder-head into the combustion chamber, and if there is any tendency to leakage by such rings during compression of the explosive gaseous mixture any fluids thus escaping are captured, withdrawn, and returned to the intake-manifold of the engine.

Similarly the lubricating oil is barred from passing upwardly by the rings on the piston into the explosion chamber and hence no difficulty is encountered by reason of the formation of objectionable carbon in such chamber and in turn the liquid or gaseous fuel and the products of combustion are prevented from passing down by the piston into the crank-case.

In my co-pending patent application Se- 130

rial Number 472,746, I have shown means for removing the fluids from around the pistons of poppet-valve type of engines, such pistons having extensions on their skirts to cooperate with the suction ports in the cylinder side walls, whereby such ports will not be uncovered during the piston stroke.

The embodiment of this invention shown in Figure 4 employs a reciprocatory sleeve between the piston and the cylinder and thus avoids the necessity for the piston-skirt extension.

In this case the piston is the same as in the other embodiment and the cylinder side wall has a port 61 therethrough connected by a pipe 62 to the separator tank or trap 48, the latter having the same connections 49 to a suction producing means such as the intake manifold of the engine, and 51 to the oiling system of the motor.

A sleeve, reciprocated by an eccentric mechanism 66, is interposed between the piston and cylinder and it has two ports 64 and 65 adapted to be brought successively into register with the cylinder port 61 during the sleeve stroke.

Thus the suction removal of the fluids from around the piston occurs over a substantial portion of the piston travel and the cylinder port is closed by the sleeve when the piston is in such position or positions that the cylinder port would otherwise be uncovered by the piston.

Accordingly, the continuous suction in the trap is not interfered with because the cylinder port is open only when the piston is in proper position for the removal of the fluid contents of its piston-ring groove.

The invention is susceptible of a variety of embodiments, the two presented being submitted by way of example only and accordingly many minor mechanical changes may be made in the structures depicted without departure from the heart and essence of the invention and without the sacrifice of any of its substantial benefits and advantages.

I claim:

1. In an internal-combustion engine, the combination of a cylinder having a port in its side-wall, an externally channeled piston reciprocatory in said cylinder, means to apply suction to said cylinder-port, a sleeve between said piston and cylinder having a port cooperating with said cylinder-port and with the piston channel means to reciprocate said sleeve, and means to supply lubricant to said cylinder, piston and sleeve.

2. In an internal-combustion engine, the combination of a cylinder having a port in its side-wall, an externally channeled piston reciprocatory in said cylinder, means to apply suction to said cylinder-port, a sleeve

between said piston and cylinder having a plurality of spaced ports adapted to cooperate with said cylinder-port and with the piston channel, means to reciprocate said sleeve, and means to supply lubricant to said cylinder, piston and sleeve.

3. In an internal-combustion engine, the combination of a cylinder having a port in its side-wall, a piston reciprocatory in said cylinder having a piston-ring groove equipped with an air-inlet port, a piston-ring in said groove, said piston having an external longitudinal groove in register with said cylinder-port and in communication with said piston-ring groove, means to apply suction to said cylinder-port, a ported sleeve between said piston and cylinder cooperating with said cylinder-port and with said longitudinal piston groove, means to reciprocate said sleeve, and means to supply lubricant to said cylinder, piston and sleeve.

4. In an internal-combustion engine, the combination of a cylinder having a port in its side-wall, a piston reciprocatory in said cylinder having a piston-ring groove equipped with a port, a piston-ring in said groove, said piston having an external longitudinal groove in register with said cylinder-port and in communication with said piston-ring groove, means to apply different pneumatic pressures to said piston-ring groove port and said cylinder port, a ported sleeve between said piston and cylinder cooperating with said cylinder port and said longitudinal piston groove, means to reciprocate said sleeve, and means to supply lubricant to said cylinder, piston and sleeve.

5. In an internal-combustion engine, the combination of a cylinder having a port in its side-wall, an open-ended piston reciprocatory in said cylinder having a piston-ring groove equipped with an air-inlet port extended through the piston-wall to its hollow interior, a piston-ring in said groove, said piston having an external longitudinal groove in register with said cylinder-port and in communication with said piston-ring groove behind the piston-ring, means to apply suction to said cylinder-port, a sleeve between said piston and cylinder having a plurality of spaced ports adapted to cooperate with said cylinder-port and with said longitudinal piston groove, means to reciprocate said sleeve, and means to supply lubricant to said cylinder, piston and sleeve.

6. In an internal-combustion engine of the Knight type, the combination of a cylinder having inlet and exhaust ports and a supplemental port in its side-wall, a reciprocatory externally channeled piston in said cylinder, inner and outer sleeves between said piston and cylinder having ports therethrough cooperating with all of said cylinder.

- der ports, means to reciprocate said sleeves, means to supply lubricant to said cylinder, piston and sleeves, and means to apply suction to said supplemental cylinder port to withdraw the contents of the piston channel through the corresponding ports of said sleeves.
7. In an internal-combustion engine of the Knight type, the combination of a cylinder having inlet and exhaust ports and a supplemental port in its side-wall, a reciprocatory externally channeled piston in said cylinder with an air-inlet port to said channel, said piston having an external longitudinal groove in register with said supplemental port and in communication with said piston-channel, inner and outer sleeves between said piston and cylinder having ports therethrough cooperating with said cylinder-port and said piston groove, and other ports coacting with said inlet and exhaust ports means to reciprocate said sleeves, means to supply lubricant to said cylinder, sleeves and piston, and means to apply suction to said supplemental cylinder-port to withdraw the contents of the piston channel through the corresponding ports of said sleeves.
8. In an internal-combustion engine of the Knight type, the combination of a cylinder having inlet and exhaust ports and a supplemental port in its side-wall, a reciprocatory externally channeled piston in said cylinder having an air-inlet port for such channel, inner and outer sleeves between said piston and cylinder having ports therethrough cooperating with all of said cylinder ports, means to reciprocate said sleeves, means to supply lubricant to said cylinder, sleeves and piston, and means to apply suction to said supplemental port to withdraw the contents of the piston channel through the corresponding ports of said sleeves, one at least of said sleeves having a plurality of spaced ports cooperating with said supplemental cylinder port.
9. In an internal-combustion engine of the Knight type, the combination of a cylinder having inlet and exhaust ports, a reciprocatory piston in said cylinder, inner and outer sleeves between said piston and cylinder having ports therethrough cooperating with said cylinder ports, means to reciprocate said sleeves, means to supply lubricant to said cylinder, sleeves and piston, and means to withdraw fluids from the chamber in said cylinder beyond the inner ends of said sleeves.
10. In an internal-combustion engine of the Knight type, the combination of a cylinder, a cylinder-head therefor, a piston reciprocatory in said cylinder, a pair of sleeves between said piston and cylinder with their inner end portions between said cylinder-head and cylinder, means to reciprocate said sleeves, means to supply a lubricant to said cylinder, piston and sleeves, said cylinder and sleeves having cooperating inlet and exhaust ports, and means to withdraw fluids from the annular chamber beyond the inner ends of the sleeves between said cylinder-head and cylinder.
11. In an internal-combustion engine, the combination of a ported cylinder, a reciprocatory piston therein, a sleeve between said cylinder and piston, the inner end of which is accommodated in an annular chamber in said cylinder means to reciprocate said sleeve, means to supply lubricant to said cylinder, piston and sleeve, and means to withdraw fluids from the chamber in said cylinder beyond the inner end of said sleeve.
12. In an internal-combustion engine of the Knight type, the combination of a ported cylinder, a cylinder-head projecting into said cylinder, a reciprocatory piston in said cylinder, a pair of ported sleeves between said piston and cylinder, means to reciprocate said sleeves, means to supply lubricant to said cylinder, sleeves and piston, means to withdraw fluids from around said piston, and means to withdraw fluids from the annular chamber between said cylinder and cylinder-head beyond the ends of said sleeves.
13. In an internal-combustion engine of the Knight type, the combination of a cylinder having inlet and exhaust ports, a reciprocatory piston in said cylinder, inner and outer sleeves between said piston and cylinder having ports therethrough cooperating with said cylinder ports, means to reciprocate said sleeves, means to supply lubricant to said cylinder, sleeves and piston, said cylinder having a chamber receiving the inner ends of said sleeves, said chamber being provided with an air inlet-port, and means to withdraw fluids from said chamber beyond the inner ends of said sleeves.

In witness whereof I have hereunto set my hand and seal.

RALPH L. SKINNER. [L. S.]
